MEANS FOR USE IN LAYING CONCRETE
PATHWAYS AND THE LIKEThomas Wass Flory, Dunstable, Bedfordshire,
EnglandApplication March 28, 1942, Serial No. 436,596
In Great Britain January 29, 1942.

6 Claims. (Cl. 25—118)

This invention relates to the laying of concrete and similar pathways and the like in situ and has for its object improved means for enabling the correct width line and level readily to be maintained, as the work proceeds, as well as generally to facilitate the operation. The improvements provided by the present invention consist in alterations of some of the members constituting the means set out in the specification of my Letters Patent No. 2,286,612.

In accordance with the present invention primary and secondary spacing members, partition strips separate from said spacing members, bridging members, and channel-section side members are provided, said spacing members being adapted to support, and prevent distortion of, said partition strips and said channel-section side members when laid on their sides on the ground with their webs vertical and facing towards one another and in conjunction with said partition strips, constitute the sides of a mould in which the concrete or the like is to be cast and each of these spacing members is disposed on the upper surfaces of said channel-section side members and is provided at each end, with a double cam device adapted to act on the edge and on the inner face of one of the flanges of a channel-section side member so that a shoulder on said spacing member may be drawn into close contact with the web of said channel-section side member, so that said spacing member itself may be brought to a predetermined level and position with respect to the channel-section side members with which it is engaged and so that the locking together of the said channel-section side members and the backing up of the separate partition strips may be effected to form a rigid frame-like mould entirely free from distortion, whilst each bridging member is arranged so that it may be disposed on, and its underside brought to the level of, the upper surfaces of the channel-section side members and is devoid of any part which projects down below said level and between said side members so that two of said bridging members may be located in juxtaposition to, and on opposite sides of, a partition strip which is to be removed, thus serving to overlie and hold down the concrete or the like during the upward withdrawal of said partition strip, and being themselves adapted to be removed by longitudinal sliding movement without damage to the surface of the laid concrete or the like.

The spacing members are of two patterns, the one, the primary spacing member, arranged for use below, and the other, the secondary spacing

member, arranged for use above, the level of the surface of the path to be laid.

For the laying of curved pathways the channel-section members may be pre-formed according to requirements.

The channel-section members, whether straight or curved are made in convenient lengths and in order that two such members may be properly aligned and secured end to end, each may have secured at its one end a fish plate adapted to fit closely within the channel-section and at the other end a clamping device such as a cam pivotal on an axis parallel with the web of the channel-section member against which web it may force the fish plate projecting from the end of the next adjacent member. By these means may be assured the correct alignment of the sides of the pathway to be laid, whether it be straight or curved.

20 The invention is illustrated by the accompanying drawings wherein Figure 1 is a plan view of parts arranged to constitute a mould for the laying of an area of a concrete pathway; Figure 2 is a similar view showing an area of the path laid and primary and secondary spacing members arranged preparatory to the laying of the adjacent area; Figure 2a shows two adjacent bays of a path laid and bridging members arranged in position preparatory to removal from the laid concrete of a partition strip; Figures 3 and 4 are enlarged sections on the lines 3—3 and 4—4, respectively, Figure 1; Figure 5 is an enlarged sectional elevation of the cam device used at the ends of the primary and secondary spacing members and at one end of a bridging member; Figures 6 and 6a are enlarged sections on the lines 6—6 and 6a—6a, respectively, Figure 2; Figures 7 and 8 are enlarged sections on the lines 7—7 and 8—8, respectively. Figure 9 is a fragmentary side elevation showing how the adjacent ends of channel-section side members are united; Figure 10 is a sectional plan on the line 10—10, Figure 9; and Figure 11 is a plan corresponding with Figure 10 but showing a modification.

45 As shown in Figures 1, 3 and 4, a mould for the laying of an area of a path consists of channel-section side members 21, 21 which are disposed with their webs vertical and facing towards one another and are located in parallel relationship by means of transversely arranged primary spacing members 22, 22, whilst partition strips 23, 23 separate from said spacing members engage the side members 21, 21 and are supported, from the sides remote from the area where the concrete is to be laid, by said primary spacing

members 22, 22. Each side member 21 is notched, as at 24 (Figures 1 and 4), at intervals along its length, to receive a hooked end 25 of a partition strip 23. Each primary spacing member 22 is of channel-section with its web uppermost and secured to the upper side of said web is a clamp having a handle 26 by means of which may be turned a double cam device shown in greater detail in Figure 5. The handle 26 is mounted on a spindle 27 which has its bearing in the body 28 of the clamp, and at the lower end of the spindle 27 is a double cam, a peripheral cam 29 which is adapted to act on the edge of the upper flange of a channel-section side member 21, whilst a face cam 30 is adapted to act on the inner face of said flange (see Figure 4). A spring washer 31 is disposed around the spindle 27 and bears against the body 28 and against a shoulder presented by the transverse face of the cam 29. As shown in Figures 1, 3 and 4 the body 28 has a horizontally extending portion 32 which rests on the top of a channel-section side member 21 and under which is secured the web of a primary spacing member 22 so that said web is supported with its upper surface level with the upper surface of the channel-section side member 21, the cam 30 serving to draw down the clamp against the upper surface of the side member 21, whilst the cam 29 draws the end of the spacing member 22 against the vertical web of said side member.

For use, the channel-section side members 21, 21 are laid on suitably prepared ground and correctly located with respect to one another by means of the primary spacing members 22, 22, for which purpose it is desirable that a primary spacing member 22 should be secured to the channel-section side members 21, 21 at each end of the lines of side members, whatever may be the length of said lines, after which the total area thus enclosed may be sub-divided by partition strips 23, laid transversely and each of which is supported by the side members 21, 21, with the notches 24 in which they engage by means of hooks, projecting pins or the like. As shown in Figure 1 the partition strips 23, 23 at each end of the first bay are supported so as to be normal to the surface of the pathway to be laid, by placing in juxtaposition thereto a primary spacing member 22 outside the partition strip 23, that is to say, on the side thereof remote from the bay where the concrete is to be laid. Similarly each succeeding partition strip 23 is supported by a primary spacing member 22 placed in juxtaposition thereto, that is to say on the right thereof, Figures 2 and 2a, if it be assumed, as set forth above, that concrete is to be laid in the left hand bay first and then working from left to right. In order that the clamping means of the spacing members 22, 22 may be operated in either direction, their cams 29, 30 should be symmetrical about a radius corresponding with a peak of the cam. When the cams 29, 30 are actuated to clamp the spacing members 22, 22 to the channel-section side members 21, 21, a slight rolling action ensues where the cams bear on the flanges of the channel-section side members 21, 21 thus causing said primary spacing members 22, 22 to fit closely against the adjacent partition strips 23, 23. If desired, longitudinally arranged shallow sub-divisional partition strips may be interengaged with the transverse partition strips 23 to produce grooves in the surface of the concrete.

33, Figures 2, 6 and 6a is a secondary spacing member which is somewhat similar to the primary spacing member 22 and has clamping de-

vices at its ends similar to those described in connection with the primary spacing member 22, but its channel-section is so arranged that when clamped in position the flanges of said spacing member 33 are upwardly directed, the lower surface of its web being drawn into contact with the upper surfaces of the side members 21 and projections 36, Figures 6 and 6a, from its underside being drawn firmly against the vertical webs of said side members 21.

When concrete has been laid in the first bay between two partition strips 23, 23, supported against the tamping pressure by the primary spacing members 22, 22, Figure 1, and the succeeding bay is to be laid, a secondary spacing member 33, Figures 6 and 6a, is located on the side members 21, 21 over the concrete already laid so as to support the transverse partition strip 23 at the beginning of the second bay, above the level of the surface of the laid area and the primary spacing member 22 adjacent to said partition strip 23 is removed, see Figure 2, and, as shown in Figure 2, is used to support the transverse partition strip 23 at the other end of said second bay on the outside and below the level of the surface to be laid in said second bay. Concrete is then laid in said second bay, rammed and smoothed. The secondary spacing member 33 is then removed from the first bay and located to support the partition strip 23 at the beginning of the third bay, i. e., on the side of said partition remote from the third bay. It is to be observed that the secondary spacing member 33 is removed just after the bay is laid and whilst the concrete is still moist, hence the depressions left by the projections 36 in the laid concrete can be filled up and any surface irregularities can be corrected with a trowel.

In order that the transverse partition strips 23 may be removed from the cast concrete when it is about to set and without breaking away the surface thereof, there are provided bridging members 33a, see Figures 7 and 8, on which the means by which they may be secured to the channel-section side members 21 are arranged so that their lower surfaces will be at the surface level of the laid pathway. Each of these bridging members 33a has, at one end, a rotatable elongated tongue 34 to engage the under surface of the upper flange of one of said side members 21 and, at the other end, a cam device 29, 30 similar to that of the primary and secondary spacing members 22 and 33. When a transverse partition strip 23 is to be removed, two of these bridging members 33a are arranged closely adjacent to the opposite sides thereof, as shown in Figure 8, the elongated tongues 34 being engaged first, after which the double cam devices at the other ends of said bridging members are actuated to grip the channel-section side member 21 at that side and at the same time to draw the elongated tongues into close engagement with the channel-section side member 21 at the other side. The partition strip 23 is then withdrawn upwardly, said members 33a, 33a serving to hold down the concrete, after which said members 33a, 33a are unclamped and slidden longitudinally over the surface of the concrete, the direction of movement being such that the rotatable elongated tongue 34 is at the trailing end. This tongue 34 is elongated so that its axis of rotation may be at such a distance from the point at which it grips the flange of the side member 21 as to permit of the required sliding movement. A slight lifting movement may be induced simultaneously if the

under-surface of the bridging member 33a be inclined downwardly at its end, as indicated at 35, Figure 7, beyond the point at which the flange of the side member 21 is gripped, to ride up said flange. As the bridging members 33a are devoid of any part which projects down below the level of the laid concrete and between said side members they may be slid longitudinally over the surface of the concrete without damage thereto.

Figures 9 and 10 show how side members 21 may be properly aligned, and secured end to end. For this purpose each has riveted at its one end a fish plate 37 adapted to fit closely within the channel-section and projecting from said end, whilst at its other end it has a clamping device in the form of a cam 39 pivotal about a vertical pin 39 to force against its web the fish plate 37 of the adjacent side member 21.

Figure 11 shows a modification of the means for aligning the side members 21, wherein the fish plate 37 is tapered slightly at its free end and wedged in tightly behind the pin 39.

In order that the functions of the different members may be appreciated fully the sequence of operations in the laying of a concrete or like path will now be recapitulated.

(a) The channel-section side members 21, 21 are laid on prepared ground, interconnected and spaced correctly by means of the primary spacing members 22.

(b) Separate partition strips 23 are dropped into position in the notches 24 and are supported below the level of the upper surfaces of the channel-section side members 21, 21 by locating the primary spacing members closely thereto, one on the left of the first partition strip 23 and the remainder on the right of each succeeding partition strip (if laying the concrete or the like from left to right). See Figure 1.

(c) Lay, ram and smooth off the concrete in the left hand, or first, bay.

(d) Locate a secondary spacing member 33 over the laid concrete and close to the partition strip 23 at the right hand end of the bay and then remove the primary spacing member at the opposite side of said partition strip. See Figure 2. If all the partition strips 23 have not been supported initially by a primary spacing member 22, that member which has just been removed should be located on the right hand side of, and close to, the succeeding partition strip 23. The second bay will then be ready for the laying of concrete therein, one partition strip 23 being supported by the previously laid concrete in conjunction with the secondary spacing member 33 and the other partition strip being supported by a primary spacing member 22. Concrete is then laid, rammed and smoothed off in the second bay.

(e) Remove the secondary spacing member 33 from the first bay in which the concrete is still in a moist state and locate said member over the concrete laid in the second bay and close to the partition strip 23 at the right hand end of the second bay.

(f) Fill up the depressions left in the concrete in the first bay by the projections 36 from the under-surface of the secondary spacing member 33, and any other irregularities and finish off with a trowel.

(g) Repeat the steps (c) (d) (e) and (f) in the succeeding bays and:

When the concrete in a bay is on the point of

taking its initial set the partition strips 23 may be removed, for which purpose

(h) Locate two bridging members 33a, 33a, on opposite sides of, and close to, a partition strip 23. See Figures 2a and 8. Withdraw the partition strip 23 upwardly and then slide off the bridging members 33a, 33a, longitudinally. If any damage to the surface of the concrete has occurred this should now be made good. Repeat this operation for the succeeding partition strips 23 so that only the channel-section side members 21, 21 and the first and last primary spacing members 22, 22 are left, and:

When the concrete in all the bays has set remove the first and last primary spacing members 22, 22 and the channel-section side members 21, 21.

The spaces left by the removal of the partition strips 23 are filled with lime mortar and smoothed off either before or after the first and last spacing members 22, 22, and the channel-section side members 21, 21 are removed.

By means of this invention, the laying, with accuracy, of concrete and similar pathways and the like in situ to any line or curve is greatly facilitated.

I claim:

1. Means for use in the laying of concrete and similar aggregate pathways and the like comprising in combination a bridging member, channel section side members and partition strips, said channel section side members constituting with said partition strips the sides of a mould in which concrete may be cast, the arrangement being such that said bridging member may be disposed on, and its underside brought to the level of, the upper surfaces on said channel section side members and adjacent to one of said partition strips, said bridging member being devoid of any part which projects down below said level and between said channel section side members and being provided at its ends with means for engaging said side members.

2. Means for use in the laying of concrete and similar aggregate pathways and the like comprising in combination a bridging member, channel section side members and partition strips, said channel section side members constituting with said partition strips the sides of a mould in which concrete may be cast, the arrangement being such that said bridging member may be disposed on, and its underside brought to the level of, the upper surfaces on said channel section side members and adjacent to one of said partition strips, said bridging member being devoid of any part which projects down below said level and between said channel section side members and being provided at one end with a double cam device and at the other end with a rotatable elongated tongue for engaging said side members.

3. Means for use in the laying of concrete and similar aggregate pathways and the like comprising in combination a bridging member, channel section side members and partition strips, said channel section side members constituting with said partition strips the sides of a mould in which concrete may be cast, the arrangement being such that said bridging member may be disposed on, and its underside brought to the level of, the upper surfaces on said channel section side members and adjacent to one of said partition strips, said bridging member being devoid of any part which projects down below said level and between

said channel section side members and being provided at one end with a double cam device adapted to act on the edge and on the inner face of one of the flanges of a channel-section side member and at the other end with a rotatable elongated tongue adapted to act on the inner face of one of the flanges of another channel-section side member, both said double cam device and said rotatable elongated tongue being adapted to secure the bridging member with its under surface in contact with the upper surfaces of the channel-section side members.

4. Means for use in the laying of concrete and similar aggregate pathways and the like comprising in combination a bridging member, channel section side members and partition strips, said channel section side members constituting with said partition strips the sides of a mould in which concrete may be cast, the arrangement being such that said bridging member may be disposed on, and its underside brought to the level of, the upper surfaces on said channel section side members and adjacent to one of said partition strips, said bridging member being devoid of any part which projects down below said level and between said channel section side members and being provided at one end with a double cam device and at the other end with a rotatable elongated tongue for engaging said side members, the under surface of the bridging member being inclined downwardly at said other end.

5. Means for use in the laying of concrete and similar aggregate pathways and the like comprising in combination a bridging member, channel section side members and partition strips, said channel section side members constituting with said partition strips the sides of a mould in which concrete may be cast, the arrangement being such that said bridging member may be disposed

on, and its underside brought to the level of the upper surfaces on said channel section side members and adjacent to one of said partition strips, said bridging member being devoid of any part which projects down below said level and between said channel section side members and being provided at one end with a double cam device adapted to act on the edge and on the inner face of one of the flanges of a channel-section side member and at the other end with a rotatable elongated tongue adapted to act on the inner face of one of the flanges of another channel-section side member, both said double cam device and said rotatable elongated tongue being adapted to secure the bridging member with its under surface in contact with the upper surfaces of the channel-section side members, the under surface of the bridging member being inclined downwardly at said other end beyond the part where it makes contact with the upper surface of a channel-section side member, whereby, when the bridging member is removed by longitudinal sliding movement, the co-action of the inclined part of its under surface with a channel-section side member will cause the bridging member to rise slightly.

6. Means for the use in the laying of concrete and similar aggregate pathways and the like, comprising in combination bridging members, channel section side members and a partition strip, said channel section side members forming with said partition strips the sides of a mould in which concrete has been cast, two of said bridging members being disposed on, and their undersides brought to the level of, the upper surfaces of said channel section side members and adjacent to and on opposite sides of said partition strips.
